UNITED STATES PATENT OFFICE.

GAETANO GENTILE, OF NEW YORK, N. Y.

MACARONI-DRYING PLANT.

1,333,406.

Specification of Letters Patent.

Patented Mar. 9, 1920.

Application filed June 3, 1918, Serial No. 237,988. Renewed January 10, 1920. Serial No. 350,681.

To all whom it may concern:

Be it known that I, GAETANO GENTILE, a subject of the King of Italy, and a resident of the city of New York, borough of Manhattan, in the county and State of New York, have invented a new and Improved Macaroni-Drying Plant, of which the following is a full, clear, and exact description.

Among the principal objects which the present invention has in view are: To provide means for maintaining a continuous circulation of dry air in the presence of suspended macaroni; to provide means for at will reversing the direction of the blow of air utilized for drying the product; to provide means for removing the heavier or humid air, and to reduce the time required for drying the macaroni.

Drawings.

Figure 1 is a plan view of a room arranged in conformity with the present invention;

Fig. 2 is a vertical longitudinal section 25 of the same;

Fig. 3 is a cross section of the same;

Fig. 4 is a detail view showing in perspective, the construction and arrangement of one of the drying racks employed in the 30 present invention.

Description.

As seen in the drawings, a drying chamber is disposed between the four walls of 35 a room, the side walls of the drying chamber being separated from the side walls of the room to form lateral passages 9. The side walls of the drying chamber are formed in the major part by doors 10, which have 40 hinges 11 on which the doors throw outward to permit access to the interior of the drying chamber and to the passageway between the racks 12 therein. The racks 12 preferably consist of angle irons arranged 45 to support a wood fillet 13, the upper edge whereof is fluted to form closely disposed pockets 14. The pockets 14 are provided to receive and hold the ends of the rack sticks 15 on which macaroni 16 is strung or disposed for drying. The racks 12 are superposed and as large a number of racks is 50 used as consistent with the height of the drying chamber.

The drying chamber, as shown in Fig. 1 55 of the drawings, is open at the opposite ends to permit free access and exit of the air

taken from and delivered to the passages 9. The air so delivered is drawn into the chamber at one end and delivered therethrough to the opposite end by a fan 17 of the reversible type. The fan 17 is disposed in a circular passage 18 formed in the wall or partition 19, which divides the two sections of the drying chamber. The fan is supported in bearings on a pedestal 20, and is driven 60 by an electric motor 21 of the reversible type. The pedestal 20 and the motor 21 are preferably mounted in a space or crevice 22 formed in the partition 19, as shown best in Fig. 2 of the drawings.

The width of the partition 19 is less than the width of the end portions of the drying chamber. The side walls of the chamber are shaped to correspond with the divergent widths, and, in consequence, impart to the 70 chamber in plan a waisted or throated central portion wherein are disposed heat-radiating coils 23, for either hot water or steam. The coils 23 are disposed between the fan 17 and the first tier of macaroni, or racks 12 80 containing the same. As each radiating coil delivers its heat, said heat passes in a column in front of and to the rear of the fan 17 to be thereby forced forward into the chamber wherein the macaroni is being 85 dried, and drawn through the opposite chamber. The heating arrangement for the drying plant is further augmented by supplementary heaters 24, opposite both ends of the drying chamber, the columns of the 90 heated air rising from these auxiliary coils being ultimately drawn in the chamber by the fan 17.

During the drying of the macaroni and as the result of the extraction of moisture 95 therefrom, the air contained in the chamber becomes impregnated with moisture and the heavier portion naturally precipitates or falls to the floor of the drying chamber. It is to remove this heavier air that there 100 is provided an auxiliary fan 25, which, as shown in the drawings, is disposed at the floor of the outer or containing chamber. The fan 25 serves to carry off the moist air 105 above referred to.

It will be understood that any source of power may be employed to drive the fans 17 and 25.

Operation.

When equipped as shown in the drawings, and as above described, a drying plant may

be operated as follows: Macaroni 16 is suspended on the sticks 15, and is then carried by hand within the drying chamber, entering through the doors 10, to be disposed at the far side of said chamber on the racks 12, and within the pockets 14 of the fillet 13.

When the chamber has become thoroughly charged, the fan 17 is started, and the air contained in said chamber is circulated, being drawn into the chamber from the surrounding room and from the passages 9 thereof over the coil 24 at one end of the drying chamber to be ejected from the other end of the drying chamber above the heaters 24 there located. The circulation is maintained for a given period, when the fan 17 and electric motor operating the same are reversed, and the circulation then inaugurated and maintained in the reverse direction. This alternation of circulation is proceeded in until the macaroni contained in the chamber is found to be dry.

During this entire operation, a fan 25 is continuously blowing from the passages 9 the moisture-laden or humid air.

It will be found that when employing an apparatus such as described, a given amount of macaroni may be dried in about fifty per cent. of the time required when employing the conventional methods.

Claims.

1. A drying plant comprising a main end-closed chamber; an auxiliary end-opened chamber contained within said main chamber, the side walls and end of said chambers being spaced apart to form lateral passages at the sides of said auxiliary chamber; a par-

tition bisecting said auxiliary chamber, said partition having an opening therethrough; 40 and means disposed in said opening for circulating air lengthwise of said chambers and alternately in opposite directions.

2. A drying plant comprising a main end-closed chamber; an auxiliary end-opened 45 chamber contained within said main chamber, the side walls and end of said chambers being spaced apart to form lateral passages at the sides of said auxiliary chamber; a partition bisecting said auxiliary chamber, 50 said partition having an opening therethrough; and a rotary fan mounted in said opening for circulating the air in said auxiliary chamber lengthwise thereof.

3. A drying plant comprising a main 55 end-closed chamber; an auxiliary end-opened chamber contained within said main chamber, the side walls and end of said chambers being spaced apart to form lateral passages at the sides of said auxiliary chamber; a partition bisecting said auxiliary chamber, said partition having an opening therethrough; and a rotary fan mounted in said opening for circulating the air in said auxiliary chamber lengthwise thereof; and 60 means for at will altering the rotary direction of said fan to reverse the circulation of said air.

In testimony whereof I have signed my name to this specification in the presence of 70 two subscribing witnesses.

GAETANO GENTILE.
